W. E. EMERY,
PROCESS FOR SEALING SHAFTS OR WELLS,
APPLICATION FILED SEPT. 19, 1918.

1,394,718.

Patented Oct. 25, 1921.

UNITED STATES PATENT OFFICE.

WALTER E. EMERY, OF PEORIA, ILLINOIS.

PROCESS FOR SEALING SHAFTS OR WELLS.

1,394,718.

Specification of Letters Patent. Patented Oct. 25, 1921.

Application filed September 19, 1918. Serial No. 254,714.

To all whom it may concern:

Be it known that I, WALTER E. EMERY, a citizen of the United States, residing at Peoria, in the county of Peoria, State of

Illinois, have invented a new and useful Process for Sealing Shafts or Wells; and I do hereby declare the following to be a full, clear, and exact description of the invention, such as will enable others skilled

10 in the art to which it appertains to make and use the same.

The present invention relates to a process of sealing a water bearing strata which may be encountered when sinking a shaft or making an excavation, and has for its object to provide a means whereby the inflow of water from the water bearing strata can be checked and held under control so that the excavation can be proceeded with and the in-

20 flow of water kept under control by any conventional pumping means. When sinking a shaft into the ground for the purpose of mining coal, ore or other substances, for the purpose of obtaining oil, gas or water, or for any other purpose, it sometimes hap-

25 pens that the shaft is inundated by an uncontrollable flow of water from a strata of water bearing earth which is encountered. When this happens the usual pumps are

30 not sufficient to remove the water, and the shaft must either be abandoned or excavation continued at considerable expense by the "vacuum and plenum" processes. Fur-

35 thermore, many operating mines have to be abandoned because an uncontrollable flow of water develops in some strata, and sections of mines have to be sealed up and abandoned for similar reasons, the coal, mineral or other ore contained in those portions of the mine

40 which are cut off being thus forever lost. This process aims to eliminate much of this loss by providing an inexpensive and effective means whereby a cement barrier can be formed around the shaft or excavation

45 at the zone where it is intersected by the water bearing strata, thereby cutting off the excess flow of water and enabling the water within the excavation to be held under control by the usual pumps.

50 Also in the case of open air coffer-dams for foundations considerable difficulty is encountered by reason of the water coming up through the bottom of the excavation during the progress of the work and the

55 lowering or driving of the coffer-dam, and after the excavation has been completed the

water usually interferes with the foundation work. This process can be utilized in connection with coffer-dams to overcome this difficulty.

60

For a full understanding of the process and the various steps incident to carrying out the same, reference is to be had to the following description and accompanying drawing, in which:

65

Figure 1 is a vertical sectional view through a partially excavated shaft showing the manner in which the process is utilized to seal a water bearing strata which is encountered when sinking the shaft.

70

Fig. 2 is a horizontal sectional view on the line 2—2 of Fig. 1.

Fig. 3 is a vertical sectional view through a coffer dam in connection with which the sealing process is utilized.

75

Fig. 4 is a horizontal sectional view on the line 3—3 of Fig. 3.

Corresponding and like parts are referred to in the following description and indicated in all the views of the drawings by the same reference characters.

Referring to Figs. 1 and 2 of the drawing, the reference character A designates a vertically disposed shaft which has been par-

80

tially sunk into the ground. This shaft has been successfully excavated downwardly through the different earth formations encountered until a water bearing strata B has been reached. A strata C of rock or

85

some hard formation is located immediately below the water bearing strata B, and in order to reach the coal or other mineral it is necessary to sink the shaft down through the water bearing strata B and the hard strata C. However, when the water bear-

90

ing strata B is reached the shaft is flooded with an uncontrollable flow of water. The usual pumps are not capable of handling this water, and ordinarily it would be necessary either to abandon the shaft or to resort to the expensive "vacuum and plenum" pro-

95

cesses. According to the present process a series of small holes 1 are bored in the water bearing strata B around the periphery of the proposed excavation. These small holes are ordinarily two inches or three inches in

100

diameter, and the spacing between the holes depends upon the quantity of water encountered, the porosity of the formation, and the depth or thickness of the water bearing strata. These holes 1 may either be vertically disposed and arranged parallel

110

to the shaft or excavation, as indicated at 1, or may be inclined and arranged at any necessary angle thereto, as indicated at 1^a. If it is desired to continue the excavation of 5 the shaft to the full dimensions, it may be found desirable to enlarge or undercut a portion of the shaft slightly above the water bearing strata, as indicated at 3, thereby enabling the holes 1 and 1^a to be bored outside 10 the dimensions of the shaft.

After the holes have been bored in the water bearing strata around the periphery of the proposed shaft, a thin grout of cement and water or of cement, sand and 15 water, is formed. If the water bearing strata is sandy, it will be preferable to omit the sand from the grout. This thin grout is forced into the holes in some suitable manner, and subjected to pressure so that the 20 cement will percolate through the earth formation surrounding the holes, thereby forming a substantially continuous cement wall around the proposed area of excavation. A tube or pipe 4 may be conveniently used for 25 filling the holes with the cement grout, the end of the pipe being initially inserted into each hole to the bottom thereof, and gradually withdrawn as the hole is filled, and compressed air may be utilized to subject the 30 cement grout to pressure so that it will thoroughly percolate through the earth formation surrounding the openings. A box 5 is shown as arranged at the upper end of 35 the pipe or tube 4, and this box may be closed so that air pressure may be maintained therein when desired. After the holes have been filled with grout the work is left 40 for a period of time and the grout allowed to set and harden. The water is then pumped out and the excavation continued, 45 the grout which has been caused to percolate through the earth formation surrounding the holes being sufficient to coöperate therewith to form a continuous concrete or cement wall 10 extending around the periphery of the excavation and stopping the great rush of water from the water bearing strata into the shaft. Of course, the flow of water 50 may not be entirely stopped, but further application of the process may be resorted to where the flow of water is still excessive, and the flow of water can be cut off to such an extent that the usual pumps will be sufficient to keep the water under control. This 55 provides an inexpensive means whereby many shafts can be saved which would otherwise have to be abandoned after the expenditure

of a large amount of money and labor in partially sinking the same.

Figs. 3 and 4 of the drawing show the 60 process as applied to a coffer-dam D. Vertical openings 7 are formed in an annular series around the coffer-dam, and the lower portions of these openings are filled with cement grout, exactly as in the previous instance. Pressure is applied to the grout so 65 that it will percolate through the surrounding earth, with the result that after it has been allowed to harden and set an annular concrete wall or barrier 8 is provided 70 around the base of the coffer-dam. This will prevent any uncontrollable flow of water and enable the work to be carried on in a most effective manner without any interference or without the necessity of working 75 under unfavorable conditions.

Having thus described the invention, what I claim as new and desire to secure by Letters Patent, is:—

1. In the art of sinking wells, the process 80 of sealing off a water bearing strata which consists in boring a series of holes which extend downwardly through the strata and are arranged in a series around the shaft, the upper ends of the holes being in communication with the shaft, filling the holes with a cement grout, and subjecting the grout to pressure whereby it is caused to percolate into the surrounding earth and to coöperate therewith to form a cement barrier 90 around the periphery of the shaft.

2. In the art of sinking wells, the process of sealing off a water bearing strata, which consists in annularly enlarging the shaft 95 above the water bearing strata, boring an annular series of holes downwardly through the water bearing strata from the enlarged portion of the shaft, said holes being arranged outside of the proposed dimensions 100 of the shaft and in a peripheral series around the same, filling the holes with a cement grout, and subjecting the grout to pressure whereby it is caused to percolate through the surrounding earth and coöperate therewith to form a cement barrier 105 around the shaft.

In testimony whereof I have signed my name to this specification in the presence of two subscribing witnesses.

WALTER E. EMERY.
